[57] **ABSTRACT**

Litter and refuse along the side of a highway is picked up by dragging a series of chains along the ground. Dragging lead chains cause the litter, such as cans, to start rolling. Each lead chain terminates with a plate to which are attached two intermediate chains. Most of the refuse rides and rolls along the top of the intermediate chains, each of which terminate with another plate. Three follow chains or bars are attached to each of these plates and the refuse rides along the top of the follow members to be swept into a basket.

HIGHWAY CLEANER METHOD**CROSS-REFERENCE TO RELATED APPLICATIONS**

This application is a continuation-in-part of application, Ser. No. 62,944 filed Aug. 11, 1970, now U.S. Pat. No. 3,669,289.

BACKGROUND OF THE INVENTION**1. Field of the Invention**

This invention relates to machines and method for picking up litter and refuse from along the edge of highways or beaches. (214/152).

A large amount of refuse and litter is strewn along the sides of the Nation's highways. The greater portion of this litter and refuse is in the form of discarded beverage cans, either aluminum or steel, but the trash also includes great numbers of glass bottles, plastic containers and, also, debris from disintegrating tires or from the cargo of trucks. In addition, there will be rocks, pieces of lumber, dead animals, such as cats, dogs, rabbits, mice, and birds, as well as the full range of discarded personal property, such as shoes and hats.

2. Description of the Prior Art

In actual practice today, most of the litter and refuse along the side of the highway is picked up by hand. Magnetic units have been devised to pick up iron objects along the highway. Also, certain units have been designed using curved fingers, which are themselves rigid, to run along the ground to pick up debris.

Certain agricultural implements, such as KINTZ 76,200; AASE 1,070,384; and FELAND 3,104,722, which are used for digging potatoes or rocks from the ground, have chains or flexible members which separate the objects from the dirt, but the objects are not picked up by the flexible members, but are picked up by blades.

FINACCHIARO 2,964,896 and WILSON 2,964,204 disclose structure similar to what I use for moving the debris from its pickup point to a bin. However, they use different methods for picking it up.

WELL 2,484,437; RUSSELL 2,448,328; and BUS-SIERE 3,151,682, disclose other approaches for similar type problems.

SUMMARY OF THE INVENTION**1. New and Different Function**

I have solved the problem of picking up the litter from the ground primarily by dragging chains over the litter. First a plurality of lead chains spaced about eight inches on center are attached to a front unit. These lead chains tend to start the litter rolling or moving as they are drug longitudinally over the litter. Each of the lead chains terminate with a connection to the bight of U-shaped plates. Each of the legs of the "U" is connected to the front of an intermediate chain, which are about 4 inches on center. The intermediate chains begin to pick up most of the trash so that it rides and bounces along the top of the chains. Each of the intermediate chains terminate with a triangular shaped plate, the intermediate chain is attached to a forward point. Three follow chains are attached to each plate. The follow chains are about 1 $\frac{1}{3}$ rd inch on centers. I prefer to use the same size chain throughout, having about a three-eighth inch chain bar and being about 1 $\frac{1}{2}$ inches in length, outside dimensions, and about 1

$\frac{1}{4}$ th inch width. Therefore, it may be seen that the follow chains are practically touching one another across the back.

The front of the lead chains and the back of the follow chains are attached to members which traverse the ground three or four inches above the ground and the major part of all of the chains and plates drag along the ground. I have found that with this dragging action of the links of the chains cause the trash to roll along and get above the chains. Once the debris is above the chains, it is swept from the follow chains with a reel, having rubber flaps, into a receptacle.

I pick up litter and refuse by dragging chains over the litter strewn ground.

OBJECTS OF THIS INVENTION

An object of this invention is to pick up trash, litter and refuse from the ground.

Other objects are to achieve the above with a method that is versatile, rapid, efficient, and inexpensive, and does not require skilled people to adjust, operate, and maintain.

The specific nature of the invention, as well as other objects, uses, and advantages thereof, will clearly appear from the following description and from the accompanying drawing, the different views of which are not necessarily to the same scale.

BRIEF DESCRIPTION OF THE DRAWING

FIG. 1 is a perspective view of an embodiment of this invention.

FIG. 2 is a longitudinal sectional view thereof taken substantially on line 2-2 of FIG. 3.

FIG. 3 is a bottom view thereof.

FIG. 4 is a sectional detail view of one of the U-shaped plates taken substantially on line 4-4 of FIG. 3.

FIG. 5 is a side elevational detail view of one of the triangular plates taken substantially on line 5-5 of FIG. 3.

FIG. 6 is a bottom detail view of the plate shown in FIG. 5.

DESCRIPTION OF THE PREFERRED EMBODIMENT

My refuse gatherer is in the form of a wheeled vehicle having hitch 10 on tongue 11, which forms a means for attaching the gatherer to a towing vehicle such as a truck or tractor. The wheeled vehicle itself forms a transport means for moving front unit 12, thus traversing litter strewn ground.

The hitch 10 is connected to the front of the tongue 11, which is connected to the front of body 14 of the wheeled vehicle which is generally a box-shaped structure. Rack 16 is on the top of the body portion, whereby litter, such as auto tires, which is too large to be picked up by the gatherer, may be manually picked up and placed therein.

Wheels 18 are mounted upon either side of the body 14 so that the vehicle is in the form of a two-wheeled cart. Each of the wheels is journaled to the rear-end of rocker bar 20. These rocker bars 20 extend from their attachment at their front end to the front unit 12. Between the front and rear, the bars 20 are pivoted by pins 22 to the body 14. Jack 24 in the form of a threaded bolt threaded inside a sleeve interconnects the front unit 12 to the front of the body 14.

Thus, when the front unit 12 is raised by the jack 24, the wheels 18 are lowered by the action of the rocker bars 20 pivoted to body 14. Because the wheels 18 are ground engaging wheels, the resulting action of this is to raise the body 14. Therefore, by raising the front unit 12 by the jack 24, not only the front unit is raised, but, also, the body 14 itself is elevated.

The jack 24 serves a dual purpose: (1) when the gatherer is being transported from one location to another and not picking up litter and refuse, the front unit 12 and the body 14 are elevated to their maximum height to be in a transport position; and (2) when the unit is working, the jack 24 acts as an adjustment to adjust the exact position the front unit 12 and the body 14 are above the ground.

Back 26 of the body 14 is made of sheet metal and is hemicylindrical in shape about a horizontal axis, which is traverse to the direction of travel of the body. The axis of back 26 is parallel to the axis of the wheels 18. The direction of travel is shown by arrow "A" in all of the FIGS. Shaft 28 of reel 30 is journaled to the body 14 coaxially with the hemicylindrical back 26. The reel 30 has four arms, each arm terminating with a rubber flap 31. The reel 30 diameter is slightly greater than the diameter of the hemicylindrical back 26 so that the rubber flaps 31 wipe the hemicylindrical back 26.

The series of chains 34 extend from the front unit 12 to lower lip 32 of the hemicylindrical back 26.

The front unit 12 is built to resemble a comb or rake. There is an upper, horizontal beam 36 which is parallel to the axis of the hemicylindrical back 26. The jack 24 is attached between this beam 36 and the body 14. Depending from the beam is a plurality of laterally spaced teeth 38 and 40. The rocker bars 20 are attached near the bottom of the two outside teeth 40. A turn-buckle 42 is attached to the bottom of each of the teeth 38 and 40. A lead chain 46 is connected to each turnbuckle 42 attached to each tooth 38, thus the lead chains are laterally spaced.

Each lead chain 46 terminates with a horizontally oriented U-shaped plate 48. The plates 48 are laterally spaced. The plate is 4 inches wide and the lead chain is connected to the top of eight 50 of the U-shaped plate 48. A sinker 44 in the form of an elongated metal bar is attached about midway the length of each lead chain 46. The purpose of the sinker 44 is to cause the lead chain 46 to have good contact with the ground.

An intermediate chain 52 is attached to each leg of the U-shaped plate 48; thus, the intermediate chains are laterally spaced. The intermediate chains are also connected to the top of the U-shaped plate 48, as seen in the drawing. By attaching the chain to the top of U-shaped plate 48, the wear upon the chains is reduced. The bottom of the U-shaped plates have wear-resistant hard surfacing material 54 welded on them. The intermediate chains 52 terminate with horizontally oriented triangular plates 56, which are laterally spaced. Each of the intermediate chains 52 is attached at the top at one of the points of the triangle 56. The triangular plate 56 is an equilateral triangle. It also has hard surfacing material 54 applied to its bottom.

Three follow members 58 are attached to the top of each of the plates 56; thus, the follow members are laterally spaced. The plates are about three inches wide and the follow members are attached about 1 1/3rd inches on center. The follow members terminate by attachment as by welding to the lower lip 32 of the back

26 of the body 14. The follow members 58 are chains for machines to be used on highway right of ways. For machines to be used on beaches, the follow members are flat bars about three sixteenth inch wide by one inch high and 16 inches long. Each of the bars has a loop on front to be attached by a link to the plates and a loop on the back to be attached by a link to lower lip 32.

The turnbuckles are adjusted so that the chains in 10 their suspension from the front unit 12 to the lower lip 32 have about 6 inches sag to them when they are unsupported. This results, when in normal operation, in the chains dragging on the ground from about the sinkers 44 to about the lower lip 32. It is necessary that the 15 chain series 34 drag along the ground for proper operation. However, it is also necessary that the chains of the series not have excessive kinks or slack in them at the joint between the follow chain 58 and the lower lip 32 so the trash in this area makes a smooth transition from 20 the follow chains to the lower lip 32 and the back 26.

Two outside chains 78 extend the entire length of the chain series 34 from the outside teeth 40 to the outside of the lower lip 32. I have found it desirable to run these two outside chains the entire length to minimize the amount of litter which is thrown to one side when the unit is operating.

I have found it desirable to limit the width of the chain series 34 to about 5 feet or 6 feet. Often the highway right-of-ways are not a plain surface, but have a 30 "crown" or other irregular surface; therefore, it is better to limit the width and to either run the gatherers as gangs or to make a series of passes to pick up the litter rather than attempting to make a wider unit which would not follow the irregularities of the terrain.

35 Immediately in front of the reel 30 is positioned bin 60. This bin is defined by the front 62 of the body 14 and by the bin floor 64 which is located above lead chains 46. Baffle 66 forms the rear of the bin 60. This vertical baffle 66 extends about half-way between the bin floor 64 and the top 68 of the body 14, which is immediately forward of the reel 30.

40 Sheave 70 upon the reel 30 provides a means for rotating the reel. Belt 72 is trained around the sheave 70 and also around drive sheave 74 located and attached to one of the wheels 18. The sheaves 70 and 74 are sized so that normal operating speeds of the gatherer, 45 the rotation of the reel is sufficient so that the trash is maintained by centrifugal force against hemicylindrical back 26 and is thrown forward along the top 68 of the body 14 into the bin 60 over the top of baffle 66.

50 Each side of the bin 60 has doors 76 so that the bin 60 may be emptied. It has been found desirable to attach a bag within the bin 60 so that the trash is collected in the bag within the bin 60; therefore, when the bin 60 is emptied, the trash is bagged. Otherwise, when the bin 60 is emptied, the trash is dumped on the ground and must be again picked up.

55 I have had good success using chains for the drag members 46, 52, and 58, on machines to be used on highway right of ways. It will be understood that the chains form flexible, pliable members and that other forms of flexible, pliable members would be suitable, however, I prefer to use chains. Also I prefer to use the three sets, the lead members or chains 46, the intermediate members or chains 52 and the follow members or chains 58. It will be understood that units which would be operable could be constructed using only the lead

chains or members and follow chains or members, however, I prefer to use the lead, intermediate, and follow chains.

Thus I have provided a refuse gatherer particularly adapted to clean litter-strewn ground along the edges of the Nation's highways. In describing my invention, I have not described many of the details of construction such as access doors, idler pulleys, bearings, and the like, because details of construction of this nature are within the skill of ordinary mechanics and a detailed description should be unnecessary to instruct ordinary mechanics in the techniques of the fabrication of such a unit. E.g., the reel pulley 70 is connected to the reel shaft 28 by a clutch or disconnect mechanism so that the gatherer may be towed at high speed without the reel windmilling.

Also, heavy woven wire screens 80 are provided along areas of the front so the excess air and dust created by the sweeping of the litter by the reel 30 is expelled. In general, the reel 30 operates as a radial-flow fan. Hood 82 attached to the center of the front 62 directs the dust downward directly in line with the towing vehicle.

The embodiment shown and described above is only exemplary. I do not claim to have invented all the parts, elements or steps described. Various modifications can be made in the construction, material, arrangement, and operation, and still be within the scope of my invention. The limits of the invention and the bounds of the patent protection are measured by and defined in the following claims. The restrictive description and drawing of the specific example above do not point out what an infringement of this patent would be, but are to enable the reader to make and use the invention.

I claim as my invention:

1. The method of picking up refuse from refuse strewn ground comprising the steps of
  - a. dragging a plurality of lead chains over the refuse strewn ground,
  - b. dragging a plurality of plates attached to the lead chains over the refuse strewn ground, and
  - c. dragging a plurality of follow members behind the plates, and
  - d. sweeping the refuse from the top of the follow members into a container.
2. The invention as defined in claim 1 wherein the items of refuse have substantially uniform dimensions and with the additional limitation of
  - e. the lateral spacing between plates being less than about the dimension of the refuse.
3. The invention as defined in claim 1 wherein the items of refuse have substantially uniform dimensions and with the additional limitation of
  - e. the width of each plate being less than about twice the dimensions of the refuse.

4. The invention as defined in claim 1 with the additional limitations of

- e. dragging a plurality of intermediate chains between the lead chains and follow members,
- f. spacing the follow members closer together than the intermediate chains, and
- g. spacing the intermediate chains closer together than the lead chains.

5. The invention as defined in claim 4 wherein the

10 items of refuse have substantially uniform dimensions and with the additional limitation of

- h. the lateral spacing between plates being less than about the dimension of the refuse.

6. The invention as defined in claim 5 with the additional limitation of

- j. the width of each plate being less than about twice the dimension of the refuse.

7. The method of lifting refuse from refuse strewn ground, the items of refuse having substantially uniform dimensions, comprising the steps of

- a. dragging a plurality of laterally spaced plates over the ground,
- b. the width of each plate being less than about twice the dimension of the refuse,
- c. the spacing between plates being less than about the dimension of the refuse, and
- d. dragging a plurality of members behind the plates.

8. The invention as defined in claim 7 with the additional limitation of

- e. dragging more members behind the plates than there are plates.

9. The invention as defined in claim 7 with the additional limitations of

- e. dragging a second set of laterally spaced plates over the ground, and
- f. dragging a plurality of members behind the plates.

10. The invention as defined in claim 9 with the additional limitation of

- g. dragging at least two members from each plate.

11. The method of picking up refuse from refuse strewn ground comprising the steps of

- a. moving the refuse, thus
- b. rolling the refuse, then
- c. running an open structure beneath the rolling refuse,
- d. running said open structure in the same direction as the refuse is moving and rolling, and
- e. transferring the refuse by sweeping from the open structure into a bin.

12. The invention as defined in claim 11 with an additional limitation of

- e. bouncing some of the refuse in addition to rolling the refuse.
